PITCHER'S RUBBER

Edward H. Love, Memphis, Tenn.

Application December 12, 1938, Serial No. 245,305

1 Claim. (Cl. 273—25)

This invention relates to improvements in foot plates, commonly designated as rubbers, which serve to give the pitcher of a baseball team a better footing and to define the location at which 5 he must stand as he starts to throw the ball to the batter.

At the present time it is customary to make use of a heavy mat of soft rubber which, under baseball rules, is six inches wide and two feet long, 10 and which is fastened down to the ground in the desired position. This mat or rubber serves for this purpose, but there is rapidly created in front of it, by the toe of the pitcher's shoe, a hole which must be constantly refilled and which even with 15 care and such constant refilling, gives an unstable and unequally acting footing which contributes often to an erratic delivery of the ball as to wildness and inaccuracy of the pitch.

The present invention is designed to correct as 20 far as possible such conditions.

The objects of the invention are:

To provide a pitcher's rubber which conforms to the rules of baseball which will correctly define the position of the pitcher, and will protect the 25 ground surface forward of the rubber proper and maintain a substantially uniform front, and ledge depth.

A further object is to provide a rubber having 30 securing means inherently protected or shielded from contact with the pitcher's foot.

The means by which the foregoing and other 35 objects are accomplished, and the method of their accomplishment, will readily be understood from the following specification on reference to the accompanying drawing, in which:

Fig. 1 is a perspective view of the rubber.

Fig. 2 is a plan of the rubber; and

Fig. 3 a transverse section on the line III—III of Fig. 2.

Referring now to the drawing in which the 40 various parts are indicated by numerals:

10 is a rectangular strip or mat of soft rubber, which, in conformity with baseball rules, is six inches wide and twenty-four inches long, but 45 which under changes in rules or other variations in conditions may obviously be of different width and length.

11 is an integral front co-extensive in length

with and extending downward from the forward edge of the mat 10 substantially at right angles thereto, and forming a shallow ledge or shoulder along such forward edge. 12 is an apron integral with and extending forward from the lower 5 edge of this shoulder. Preferably the mat, ledge and apron are of substantially uniform thickness, in the instant example being about one inch thick. The height of the ledge is relatively much less than the width of the mat and the 10 apron somewhat wider, the apron establishing the depth of the ledge.

13 are spikes having thin flat heads 14, which heads are embedded in the mat and apron approximately at the center of its depth. All the 15 spikes may be of equal length, or if desired, the spikes at the forward edge of the apron somewhat shorter.

In placing the rubber the ground surface 15 is shaped to conform to the under surfaces of the 20 mat and of the apron, and to the back of the ledge so as to solidly support each thereof. The rubber with the embedded spikes is positioned over this prepared surface and the spikes driven down to solidly hold the structure in place. 25

In ordinary use the pitcher stands on the mat portion of the rubber as in using the ordinary type mat with the toe of one foot ordinarily overhanging the forward edge, and makes the pitch. As the pitch is completed the apron 12 30 protects the underlying earth and prevents the under-cutting of the ground in front of the mat, and at the same time presents a yielding surface for the spikes or cleats of the shoe. 35

I claim:

An article of the class described, comprising an elongated rectangular mat having a co-extensive, relatively shallow edge portion extending downward therefrom, and a co-extensive rectangular apron extending forward from the lower 40 edge of said edge portion, said mat, edge portion and apron being an integral structure of soft rubber; and securing means comprising a plurality of flat headed spikes, said spike heads being embedded in said mat and said apron and 45 said spikes extending therebelow.

EDWARD H. LOVE.
